UNITED STATES PATENT OFFICE.

HENRI FRANCART, OF HERNE HILL, LONDON, ENGLAND.

FURNACE, KILN, OVEN, AND THE LIKE.

1,314,486.

Specification of Letters Patent. Patented Aug. 26, 1919.

Application filed March 26, 1919. Serial No. 285,351.

To all whom it may concern:

Be it known that I, HENRI FRANCART, a subject of His Majesty the King of Belgium, and resident of Herne Hill, in the county of London, Kingdom of England, have invented certain new and useful Improvements in Furnaces, Kilns, Ovens, and the like, of which the following is a specification.

The present invention relates to industrial furnaces, kilns, ovens and the like, used for subjecting metals or other material or substance to heat-treatment such as is necessary in the manufacture of bricks, pottery, annealing, baking, firing or fusing articles. In ovens of large size of the type wherein use is made of direct heating by reversed flames, unequal heating is liable to occur due on the one hand to the slowness with which the products of combustion pass down, over, or through the articles to be heat-treated, and on the other hand to the tendency of the flames to take the shortest path on their way to the device which sets up the draft.

The object of the present invention is to obviate this disadvantage by setting up, independently of the draft, a powerful and continuous circulation of the products of combustion through or around the articles to be heat-treated in order that the said articles may be maintained at a substantially constant temperature throughout the whole period of treatment, thus insuring the carrying out of the heat-treatment-operation in a more efficient manner than in furnaces or ovens as heretofore constructed.

To this end the furnace within which combustion is effected is in open communication at its upper end with the treatment-chamber so as to permit the passage of the products of combustion from the former into the latter, as is always done in reversed-flame furnaces. In accordance with the present invention the lower part of the furnace is in similar communication with the lower part of the treatment-chamber so that the heat set up in the furnace by the combustion of the fuel therein causes a continuous circulation of the gases in a downward direction through the treatment-chamber, the circulation being maintained by reason of the difference in density of the streams of gases within the two parts, the moving mixture moving upward by reason of its lower density and passing through the upper aperture in the dividing wall into the treatment-chamber, while the relatively cooler gases

already in the treatment-chamber flow downward by reason of their greater density and pass into the furnace through the lower aperture, the circulation being maintained in the same direction so long as the temperature within the furnace is in excess of the temperature within the treatment-chamber.

Preferably a fuel-gas is used as the combustible in the furnace. The effect of admitting and burning the fuel at the lower part of the furnace is to further accelerate the gaseous circulation because the combustion of the gas, in addition to the thermodynamic effect and with or without the admission of air into the furnace produces a suction-effect at the bottom of the combustion chamber which assists in drawing in the gases from the treatment-chamber into the lower part of the furnace. The effect of the circulation of the gaseous current is to convey the heat from the furnace to the material under treatment in the treatment-chamber, the gaseous current remaining at high temperature during the process of rapid circulation.

In carrying the invention into practice, a plurality of furnaces may be employed in combination with a single treatment-chamber, or conversely a single furnace may be employed in combination with a plurality of treatment-chambers.

The invention is hereinafter described with reference to the accompanying drawings, which show diagrammatically a construction in accordance with the present invention, but I do not limit myself to the construction described and illustrated.

Figure 1 is a vertical section on the line A—B, Fig. 2 of a kiln in accordance with the present invention, and comprising a plurality of furnaces connected in parallel with a common treatment-chamber, such an arrangement illustrating the invention as it would be applied for the purpose of heating a tunnel-oven, the parts being shown in perspective for the sake of clearness.

Fig. 2 is a horizontal section.

Referring to the drawings, it will be seen that the kiln comprises a plurality of furnaces 3, 3 each consisting of a vertical cell containing an assemblage 4 of cellularly arranged or checker refractory brickwork serving as a heat accumulator. Each furnace is separated from the common treatment-chamber 5 by a common dividing wall 6, that part of said wall appertaining to each

furnace being provided at its upper part with a through passage 7 and at its lower part with a similar passage 8.

To prevent loss of heat by radiation or conduction, the furnace is inclosed by brick-work walls 9 coated with a layer of earth 10.

11 are passages which lead the gases used as the combustible from the main fuel-conduit 12 to the individual furnaces 3, each passage 11 being provided with a fuel-controlling valve 13 for regulating the temperature within the corresponding combustion-chamber.

14 are passages serving to deliver air from the main air conduit 15 to each individual furnace 3, each passage 14 being provided with an air-controlling valve 16 for regulating the amount of air delivered to each furnace.

20 17 is a conduit leading to a chimney not shown; 18 is a traveling table for carrying the articles to be treated into the furnace; and 19 is a door for closing the charging-opening of the furnace.

25 In operation, the gases pass upward through the furnace and downward through the treatment-chamber, the gases tending to keep in continuous movement during the heating operation, thus preventing the formation of pockets in which the temperature may be either above or below the required temperature with consequent detriment to the success of the heating operation. The gases, while circulating as above set forth, 30 are also subjected to a force directed along the longitudinal axis of the treatment chamber and set up by the draft of the chimney, with the result that they follow in effect a helicoidal path as shown clearly by 35 the arrow 17 in Fig. 1.

If desired, the kiln as above set forth may form part of a tunnel oven divided into three zones the first of which is an initial heating zone, the second the maximum heating zone, while the third may be a cooling zone.

The air necessary to support combustion may be drawn into the furnace by the draft

set up by the chimney or the like and may be caused to pass over the articles in the cooling zone, thus making good the amount of air which has been used up in the combustion-process.

For the purpose of regulating the circulation of the gaseous currents, registers or 55 controlling dampers may be fitted to the openings 7 and 8 or to the conduit 17 hereinbefore described.

What I claim is:

1. A furnace, kiln, oven and the like, comprising an outer shell having a longitudinal treatment chamber embodying side walls which extend upwardly for connection in the top of the treatment chamber, said side walls being provided at their top and bottoms with pairs of openings, said side walls being spaced from the outer shell, transverse walls disposed between the side walls and outer shell and forming a plurality of separate furnaces, each furnace having communication with a pair of upper and lower openings, means for supplying a gaseous fuel to each furnace, and a stack communicating with one end of the treatment chamber.

2. A furnace, kiln, oven and the like, comprising an outer shell having a longitudinal treatment chamber embodying side walls which extend upwardly for connection with the top of the treatment chamber, said side walls being provided at their top and bottom with pairs of openings, said side walls being spaced from the outer shell, transverse walls disposed between the side walls and outer shell and forming a plurality of separate furnaces, each furnace having communication with a pair of upper and lower openings, a filler of checker brick work arranged within each furnace, said filler terminating at said openings to leave them unobstructed, means to supply a gaseous fuel to each furnace, and a stack communicating with one end of the treatment chamber.

In testimony whereof I have hereunto signed my name.

HENRI FRANCART.
